UNITED STATES PATENT OFFICE.

LAWRENCE L. McCULLOUGH, OF KANSAS CITY, KANSAS.

TRACK-MOVING APPARATUS.

No. 860,761.

Specification of Letters Patent.

Patented July 23, 1907.

Application filed August 11, 1906. Serial No. 330,158.

To all whom it may concern:

Be it known that I, LAWRENCE L. McCULLOUGH, a citizen of the United States, residing at Kansas City, in the county of Wyandotte and State of Kansas, have invented certain new and useful Improvements in Track-Moving Apparatus, of which the following is a specification.

In many instances it becomes necessary, or desirable to shift or move a considerable length of railway track 10 sidewise. This may occur in construction work, and as a particular example, it may be noted that in plants for burning ballast in the open air, such shifting of a long length of track may be necessary every day.

The objects of the present invention are to provide 15 means whereby such shifting or moving of the track may be done readily and economically by suitable machinery, thereby avoiding the larger part of the manual labor heretofore required to do such work and also lessening the time required. I accomplish these objects 20 by means of the apparatus shown in the accompanying drawings, in which:

Figure 1 is a side elevation of a car provided with apparatus embodying this invention, Fig. 2 is a top plan view of the same, Fig. 3 is a modification showing a 25 winding drum for the guide or controlling cable, Fig. 4 is a detail showing the track engaging end of the boom, Fig. 5 shows the plate on the end of said boom, and Fig. 6 is a detail showing a plan view of the rail engaging wheels.

As shown in Figs. 1 and 2, 7 represents a car of any ordinary or preferred form of construction, for instance an ordinary flat car, upon which is mounted a boom 8. This boom is preferably mounted so that it may be swung in either a vertical or a horizontal plane. For 35 this purpose it is rigidly secured to a cross beam 9, which is carried in bearings 10 and 11, and is braced by a brace 12 reaching to one end of the beam. The bearings 10 and 11 consist of straps which are bolted to the car and pass around the beam, the former is only long enough to 40 allow the beam to rotate therein when the boom is to be raised or lowered, but it also acts as a pivot to support the beam to allow for the limited horizontal swing of the boom. The other bearing, 11, is made considerably longer and not only allows the boom to be swung in a 45 vertical plane, but also allows the beam a sufficient horizontal movement to accommodate the horizontal movement of the boom. The beam is provided with bearing plates 13 where it engages with the strap 11, and these plates are preferably provided with guide flanges 50 14 which engage with the sides of the strap 11.

At the outer end of the boom is attached the devices for engaging with the track rails to move the track. These consist primarily of a plate 15 which is rigidly secured to the lower side of the beam, as shown in Fig. 4, 55 and a second plate 16, pivotally connected to the first plate at 17, and carrying two grooved wheels 18 which

engage with the head of the rail. This pivoted arrangement of the wheels is to allow the device to readily pass over any fish plates or other obstructions on the rail without danger of being thrown off. In order to limit 60 the throw of the plate 16, it is provided with two pins 19 which engage with slots 20 in the plate 15.

While I have found this device which engages with only one of the rails sufficient for practical purposes, yet it is at times desirable to have such a method of 65 attachment as will admit of the track being raised at the same time that it is being shifted sidewise. For instance, when the track has settled down into the mud, it is desirable to raise it in order that it may be moved more easily than if merely slid over. This is 70 accomplished by having an arm 21 near the end of the boom which extends across the track and carries a wheel 22 which engages with the other rail, and which is held in contact therewith by means of a suitable spring, such as the spring 23 which bears against the 75 slide bearing 24.

In order to raise and lower the boom 8, I have provided a rope or cable 25 which is attached to the outer end thereof and which runs up over a pulley or sheave 26 on a mast 27 and down to a winding drum 28. This 80 drum is shown with a hand crank 29, but of course it may be driven by power in any well known way.

The boom is swung in a horizontal plane by means of a second rope or cable 30 which is also attached to the outer end thereof, but which passes around a pulley or sheave 31 in the outer end of the beam 9 and then to a piston rod 32 of a power cylinder 33 which is located on the car 7. This cylinder is provided with steam from a boiler 34 through a pipe 35. The movement of the piston is controlled by a three way valve 90 36 having a handle 37, and an exhaust outlet 38. Other means may of course be used for swinging the boom, and as an example, the winding drum 39 may be used in place of the power cylinder.

When this apparatus is used, a locomotive pushes the 95 car forward, and the operator swings the end of the boom out by admitting steam into the cylinder 33, thereby drawing on the cable 30. This will cause the track to be shifted to one side and as the car continues to move forward the track will be continuously shifted 100 in advance. On account of the frequent irregularities in a track and where curvature occurs, it becomes necessary to have control of the boom and this is provided by the power cylinder and its controlling valve. If the operator sees that the track is being shifted too 105 far, he turns the valve so that the steam will be exhausted from the cylinder and the pressure on the boom will swing it in. He can also at any time again swing the boom out by admitting more steam to the cylinder. After the track engaging device has been arranged, the 110 boom may be raised and held by the cable 25 and winch 28 so that the wheels will constantly tend to

raise the track as the apparatus moves forward, thereby assisting in the operation of shifting the track. This device may also be used to swing the boom up out of the way when the apparatus is to be moved for some 5 distance, or when another car is coupled at that end of the car which carries the boom.

Having thus described my invention, what I claim and desire to secure by Letters Patent is:

1. A track shifting apparatus comprising a car, a boom 10 on said car for shifting the track, and a device at the end of said boom for engagement with both of the rails of the track.
2. In an apparatus for shifting railway tracks laterally, the combination of a car, a boom mounted on said car and 15 pivoted to swing both vertically and horizontally, and means for swinging said boom horizontally while the apparatus is in operation.
3. In an apparatus for shifting railway tracks laterally, the combination of a car, a boom projecting from said car and adapted to swing both vertically and horizontally, and 20 means for swinging said boom in either direction while the apparatus is in operation.
4. In an apparatus for shifting tracks, the combination

of a car, a beam pivoted at one end of said car, a boom secured to said beam, wheels at the end of said boom for 25 engaging with both of the track rails, and means for swinging said boom vertically and horizontally while the apparatus is in operation.

5. The combination with a boom for shifting a track, of a plate pivoted to the free end of said boom and supported thereby, and grooved wheels carried by said plate. 30

6. The combination with a boom for moving a track, of a device pivoted to said boom and adapted for engagement with one of the track rails, a cross arm reaching to the other rail and a wheel on said arm for engagement 35 with the last mentioned rail.

7. The combination of a car, bearing straps at the end of said car, one of said straps being longer than the other, a beam pivotally supported by said straps, a boom carried by said beam, yielding rail engaging devices at the end of 40 said boom for shifting or raising the track, a cable and winding drum for raising said boom, and a second cable and power cylinder for swinging said boom sidewise.

LAWRENCE L. McCULLOUGH.
